United States Patent Office.

S. LLOYD WIEGAND, OF PHILADELPHIA, PENNSYLVANIA, ASSIGNOR TO
WALTER J. BUDD, OF SAME PLACE.

Letters Patent No. 82,460, dated September 22, 1868; antedated September 4, 1868.

IMPROVEMENT IN STEAM-GENERATORS.

The Schedule referred to in these Letters Patent and making part of the same.

TO ALL WHOM IT MAY CONCERN:

Be it known that I, S. LLOYD WIEGAND, of the city of Philadelphia, and State of Pennsylvania, have invented certain new and useful Improvements in Steam-Generators; and I do hereby declare the following to be a full, clear, and exact description thereof, reference being had to the accompanying drawings, and the letters of reference marked thereon.

The nature of my invention consists in applying, to that class of steam-generators or boilers in which double tubes are employed, oblique or spiral wings or guides, which operate by imparting to the contents of such boilers a rotary motion, and thus developing a centrifugal or tangential force, by which means I am enabled to improve the efficiency of the heating-surfaces, as well as to insure a more thorough circulation of the contents of the boiler, and thus promote the cleanliness thereof in a manner that will hereinafter appear.

Figure 1 shows a sectional elevation.

Figure 2 shows a side elevation partly in section.

Figure 3 shows a tube in section, together with a portion of the tube-plate and a deflecting-cap marked *d*.

The remaining figures represent parts in detail.

Upon the external surface of the internal tube *D*, I fix oblique or spiral projections, *b b b*, &c., in the form of separate fins or wings, as shown in Figure 8. These fins or wings *b* may be made of uniform pitch, but I believe that they operate best to be made of accelerated pitch, or what is known to some mechanics as a "gain-twist." They may project horizontally or at right angles to the axis of the tube to which they are attached, or they may be inclined upward, as shown in fig. 3, and do not require necessarily to be fastened to the internal tube, but would be equally efficient and operative if fastened to the internal surface of the external tube *B*, or if in any other way secured in position in the annular space between the internal tube *D* and the external tube *B*.

The lower portion of the external tube *B* is closed by a cap, *M*, and the upper portion or end of the tube *B* is inserted in the conical or bell-shaped adjutage *C C*, which adjutage may be either a component part of the tube-plate or bottom of the boiler-body *G*, or a part of the tube *B*, or a separate piece, and facilitates the flow from the tubes *B* to the vessel *G*.

The internal tube *D* does not reach to the bottom of the cap *M*, but is prevented from so doing by the projection or fluted pyramid *N* contained in the cap *M*, and is long enough to reach up into the body, *G*, of the boiler or steam-generator.

By increasing the number of wings, *b*, or fins around the tube *B*, at the upper portion within the adjutage *C*, I form a winged guide resembling somewhat in appearance the guide of a Jonval turbine, as shown in Figure 11.

The operation of the wings *b b* in this instance is the same as the others, *b b*, in the annular space below between the external and internal tubes.

In the upper portion of the internal tube *D*, I form mouths, *c c c*, resembling those of a central-vent water-wheel, as shown in Figure 7, which shows a section in the plane *x y*, Figure 4, which mouths *c c* are directed toward the rotating current produced by the wings *b b b*, &c. Over the top of the tube *D*, I sometimes place a dome, *d*, shown in figs. 1, 3, 4, 5, and 6, which dome *d* is composed of wings, *e e e e*, that are curved inward, so as to direct the rotating current therein contained toward the mouths *c c c* of the internal tube *D*.

The form of the upper portion of the internal tube may be varied without essentially altering its characteristic properties, upon which its utility depends. Thus, in figs. 1 and 2 it is straight or prismatic, in fig. 3 it is conical, in fig. 4 more conical, and, in Figure 9, of the form of a leaf-bud, or it may be expanded to the form of a mushroom, as shown in Figure 12, in which case the mouths *c c c* are best placed upon the under side only, and the top made with small perforations.

The diaphragms *E E' E'' E'''* are for the purpose of breaking up bubbles of steam, and insuring a more nearly uniform liberation of the steam from the water-surface in all parts of the vessel *G* than would otherwise be obtained.

The hand-hole plate O, shown in Figure 10, separately, is used with the head of the bolt P fitting easily in the pocket f, and, by means of the bridge Q and nut R, drawn home to its bearing, as shown in fig. 2.

The operation of the generator is as follows:

Upon the tubes B B B and D D D and lower portion of the vessel G being filled with water, so that the perforated diaphragms E E' and E'' are submerged, and heat being applied to the tubes B B, the water in the annular spaces between the tubes B and D becomes heated, and consequently specifically lighter than that which is cooler in the internal tube D; therefore, the heavier column in D descends and raises the lighter column in the annular spaces, and as the water in D passes into the annular spaces, it in turn becomes heated and lighter, and the action thus becomes continuous.

The water, in rising in the annular spaces, meets the spiral wings b b b, and acquires a rotary motion, which being attended with a development of a centrifugal force so soon as any steam is formed in the annular spaces, the water being denser than the steam, and therefore possessing greater centrifugal force than the steam, is forced into intimate contact with the internal surfaces of the tubes B, and the steam lies nearer to the internal tube D in the ascending column. The rising and rotating motion of the columns in the annular space continuing, upon reaching the conical adjutages C C, the water and steam pass, by reason of their centrifugal force, into the more remote parts of the vessel G, but in so doing create an eddy or rotating current around the upper portions of the tubes D, and this revolving current is caught by the mouths c c c of the internal tubes D, and the supply of water to the descending columns in the tubes D is maintained, and this effect is secured more certainly by the revolving current issuing from the adjutages C meeting the deflecting wings e e e e of the domes d and determining the revolving current towards the mouths c c of the internal tubes. At the same time the wings e e e, by breaking up the steam-bubbles, facilitate their easy separation from the water as they rise to the surface.

I do not broadly claim as my invention the use of spiral guides to produce rotation of the contents of vertical or inclined boiler-tubes, being aware that continuous spiral guides of uniform pitch have been proposed for that purpose; those, therefore, I distinctly disclaim; but

What I claim as my invention, and desire to secure as such by Letters Patent, is—

1. The oblique or spiral deflectors or guides in double boiler-tubes, substantially as shown and described.
2. The tangential or spiral mouths, as shown, for conducting a supply of fluid to the descending columns in double tube-boilers, as shown and described.
3. The deflecting caps or domes, or the equivalents thereof, substantially as shown and described.
4. The conical adjutages C C, substantially as shown and described.

In testimony whereof, I have hereunto affixed my signature in the presence of two subscribing witnesses.

S. LLOYD WIEGAND.
